UNITED STATES PATENT OFFICE

JOSEPH BLOCK, OF BROOKLYN, NEW YORK

ELECTRIC DISPLAY DEVICE

Application filed September 12, 1930. Serial No. 481,545.

This invention relates to electric display devices such as signs and the like articles and the methods of making the same.

The invention is directed to a display device or sign having means for illuminating the letters, numbers or other portions thereof and it is an object of this invention to provide a neat, compact and rugged device of the character described, which shall be comparatively inexpensive to manufacture, simple and easy to construct and assemble, which shall be provided with means for preventing tampering with or loosening of the parts thereof after the same is assembled, and which shall yet be attractive in appearance and practical and efficient to a high degree.

A still further object of this invention is to provide a highly improved and simple and economical method of constructing a device of the character described.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claims.

In the accompanying drawings, in which is shown one of the various possible illustrative embodiments of this invention,

Fig. 1 is a front elevational view of a display device embodying the invention;

Fig. 2 is a cross-sectional view taken on line 2—2 of Fig. 1;

Fig. 3 is a fragmentary, top plan view of a portion of one of the letters of the sign with the bulb removed;

Fig. 4 is a cross-sectional view taken on line 4—4 of Fig. 1;

Fig. 5 is a rear view of the socket housing and socket shell; and

Fig. 6 is a wiring diagram illustrating the electrical connection of all of the sockets in the device.

Referring now in detail to the drawings, 10 designates a display device embodying the invention, here shown in the form of a sign, it being understood however, that the invention

may also be embodied in various other forms of electrical display and ornamental devices. The sign 10 comprises a front portion 11 made of molded electrical insulating material, such as phenol-condensate products or the like material, and a preferably flat rear cover 12. Said front portion 11 is provided with a front wall 15 and side walls 13, the cover 12 being fixed, in any suitable manner, to the rear edges 14 of said side walls. The front wall 60 or surface 15 is formed with integral depressed, channeled or sunken portions 16, forming letters, to be illuminated. For the purpose of illustration only, the sign shown in Fig. 1 is formed with the word "Soda", it being understood however, that the sign may be provided with depressed portions forming other words, symbols; figures or decorative or ornamental portions. The inner surface 17 of the channels 16 may be curved or otherwise 70 shaped to form a suitable light reflecting surface for the purpose hereinafter described.

Each of said channels 16 is formed with a plurality of suitably spaced, integral, rearwardly extending tubular portions 18 each 75 having a cylindrical opening 19 communicating with the channel. Each tubular portion 18 is further formed with a portion 20 of a diameter slightly greater than that of the opening 19. The rear edge 21 of said cylindrical portion 18 preferably lies substantially flush with the rear edges 14 of said side walls 13. Each of said tubular walls 18 is formed with a pair of transverse diametrically disposed notches, slots, or grooves 22 at the rear 85 edge 21 thereof, for the purpose hereinafter appearing. Received within said tubular opening 19 of the cylindrical portion, is an electric lamp base receiving shell 20a having a flaring mouth or rim 23, preferably formed 90 with a serrated edge 24, biting into or pressed against the inner surface of portion 20.

It will now be understood that there are a plurality of spaced cylindrical portions 18 receiving the socket shells 20a. A number of 95 shells 20a may be interconnected in series circuit in the well known manner. Each piece of interconnecting conductor wire 25 is soldered at one end 26 thereof to the central contact 27 of one shell, and the opposite end 28 of said 100

piece of wire is connected to the side wall of the next adjacent shell. The wires 25 preferably pass into the interior of the cylindrical housings 18 thru the grooves 22. The rear portion of the housing 18 as well as the grooves 22 is filled with sealing material 30, such as wax or pitch, said sealing material being hardened to prevent tampering with or looseness of the connections between the wires 25 and the socket shells 20a. The entire sign may be provided with a single outlet, as for instance by interconnecting a plurality of sets 32 of series connected sockets 20a, to each other, in parallel, as shown in Fig. 6 of the drawings, whereby only a single pair of conductors 40, 41 need extend from the sign for connection to a suitable source of electric power. The connection or splice 42 for the various sets of series connected sockets may be made within any of the spaces or chambers 43 within the sign between the tubular housings 18, and the rear wall 12 may be formed with a suitable opening for receiving the conductors 40, 41. If desired, the front portion 11 may be provided with a rearwardly extending tubular portion similar to portion 18 for receiving the splice, which may be covered with sealing wax or the like material to prevent tampering.

Screwed within each of the socket shells 20a is an electric lamp 45 having a base 46 and a mushroom shaped bulb 47. The top surface 48 only of the bulb is preferably painted or colored, the rear surface 49 only of said bulb being left clear, whereby the light from the filament may be reflected rearwardly to the reflecting surface 17. The outer surface 50 of the front wall 15 forming a background for the letters, is preferably colored contrasting to the curved surface 17 of said letters, the latter surface preferably being white or of the like color whereby said channels or letters 16 are brightly illuminated by the light from the bulbs.

The illuminated or displayed sign elements furthermore reflect light outwardly and hence illuminate a space about the sign.

As illustrated in Fig. 4, the light from the bulbs is also reflected at the curved end surface 53 of the channel 16 so that with a few bulbs the entire letter may be effectively illuminated.

In making the sign, in accordance with my invention, the portion 11 is molded with the proper channels or letters 16 and tubular portions 18 formed therein. The socket shells 20a are then forced into the openings 19, the serrated edges 24 thereof biting into the surface 20 to form a strong, clamping engagement for the shell, whereby loosening or movement of the latter is effectively prevented. The rim 23 of the shell is preferably furthermore formed with spaced notches 24a to give said rim a slight flexibility or resiliency whereby a more effective clamping con-

nection between said rim and the surface 20 is had. The sealing material 30 is tamped while still in moldable state into the rear of the tubular housing 18 and tightly packed and then allowed to cool. After the sealing material has cooled, the same forms a further securing means for preventing loosening of the socket shell. Obviously, furthermore, the soldered connection between the wires 25 and the socket shell is thereby prevented from becoming loose.

It will be noted that the tubular portion 18 forms an effective housing for the screw shell 20a thereby obviating the necessity for an additional housing for said shell.

It will thus be seen that there is provided a device in which the several objects of this invention are achieved, and which is well adapted to meet the conditions of practical use.

As various possible embodiments might be made of the above invention, and as various changes might be made in the embodiment set forth, it is to be understood that all matter herein set forth or shown in the accompanying drawings is to be interpreted as illustrative and not in a limiting sense.

Having thus described my invention, I claim as new and desire to secure by Letters Patent:

1. A display device comprising, in combination, a member made of electrical insulating moldable material having a front wall, a rearwardly depressed portion integrally formed with said wall, and an integral tubular portion extending rearwardly from said depressed portion, a socket shell received in said tubular portion, conductor wires connected to the wall and central contact of said shell, and sealing material within the rear of said tubular portion.

2. A display device comprising, in combination, a member made of electrical insulating moldable material having a front wall, a rearwardly depressed portion integrally formed with said wall, and an integral tubular portion extending rearwardly from said depressed portion, a socket shell received in said tubular portion, conductor wires connected to the wall and central contact of said shell, and sealing material within the rear of said tubular portion, said tubular portion being formed with a pair of transverse diametrically disposed slots at the rear thereof, receiving said conductor wires.

3. A unitary sign comprising a front member having a flat surface constituting a background, a plurality of integral channeled portions depressed from said front surface, each channeled portion conforming to a part of the sign to be seen against said background, a plurality of tubular members extending from said channeled portions, and lamps mounted in said tubular members and extending into said channeled portions.

4. A unitary sign comprising a front member having a surface constituting a back-ground, a plurality of depressed portions each having a configuration of a part of the sign to be seen against said back-ground, and illuminating means in said depressed portions, said depressed portions having reflecting surfaces to thereby constitute reflectors for light from said illuminating means.
- 5 5. A unitary sign comprising a flat front wall constituting a back-ground for the sign and having integral depressed portions conforming in configuration to elements of the sign viewed against said back-ground and 10 having light reflecting surfaces, tubular extensions integrally formed with said depressed portions, lamp sockets mounted in said tubular portions, and lamps in said sockets 15 projecting into said depressed portions, said 20 lamps having front portions and side portions, the front portions being less transparent than the side portions, whereby to obtain the effect of indirect illumination by the 25 light passing through the side portion of the lamps to the reflecting surfaces of said depressed portions.

In testimony whereof I affix my signature.
JOSEPH BLOCK.
